LOCK

Oscar F. Ritterbusch, Chicago, Ill.

Application April 25, 1936, Serial No. 76,439

11 Claims. (Cl. 292—97)

The invention relates to locks and is particularly adapted to be embodied in locks of the type shown and described in U. S. Letters Patent 1,907,267 granted to me May 2, 1933, and in my pending application Serial No. 745,261 filed Sept. 5 24, 1934.

An object of the invention is to provide a lock which will hold a door against lateral movement relative to the door frame and thus prevent rattling of the door in the frame.

Another object of the invention is to provide an improved lock of the kind described which is constructed so that it will be very difficult for an unauthorized person to open the door when the door is locked.

Referring to the accompanying drawings:

Fig. 1 is a vertical longitudinal section taken through a lock which embodies the invention, the lock being shown mounted in a door which is hinged in a suitable door frame.

Fig. 2 is a horizontal section taken on line 2—2 of Fig. 1.

Fig. 3 is a section taken on the same line as Fig. 1 but showing parts of the lock in changed positions.

Fig. 4 is a section taken on line 4—4 of Fig. 3.

Fig. 5 is a section taken on line 5—5 of Fig. 3.

Fig. 6 is a section taken on line 6—6 of Fig. 1, and

Fig. 7 is a section taken on line 7—7 of Fig. 3.

Referring to the drawings, the reference character 10 designates a door which is mounted in the door frame 11 by hinges (not shown). The door 10 is equipped with the improved lock which is designated generally by the reference character 12.

Lock 12 comprises a keeper 15 which is pivoted by a pin 16 in a housing member 17, the member 17 being fixed in the recess 18 provided in the door frame 11. A spring 19 disposed in the housing 17 has one end secured to a pin 19a, the other end of the spring 19 being in engagement with the keeper 15. The keeper 15 has a corner 15a which rides upon the spring 19 when the keeper 45 15 is displaced angularly from the position wherein it is shown in Fig. 2 to the position wherein it is shown in Fig. 4. It will be readily understood that during the initial portion of the movement of the keeper 15 from the position wherein it is shown in Fig. 2 to the position wherein it is shown in Fig. 4, the spring 19 will tend to return the keeper 15 to the position wherein it is shown in Fig. 2 but during the final portion of the movement of the keeper 15 to the position wherein it is shown in Fig. 4, the spring will urge the keeper 15 yielding in a counter-clockwise direction (Figs. 2 and 4). The surfaces of the keeper 15 adjacent the corner 15a are identified by the reference characters 15b and 15c. 55 When the spring 19 engages the surface 15b, the

spring tends to rotate the keeper in a clockwise direction (Figs. 2 and 4). When the spring 19 engages the surface 15c, the spring tends to rotate the keeper 15 in a counter-clockwise direction.

The keeper 15 comprises arms 22 and 23, the arm 22 being engaged by a plunger or wedge member 25 when the door is in its closed position (Figs. 3 and 4). For this purpose, the arm 22 is provided with an aperture 22a through which the lower end of the wedge member 25 passes.

The wedge member 25 is disposed in a fabricated housing 26 which, in turn, is disposed in a recess 27 provided in the free edge of the door 10. The housing 26 comprises a striker plate 30

provided with a slot 31 through which the arm 22 may pass to engage the wedge member 25 and a bar or plate 33, the plate 33 being carried by a plunger 34 which is slidably journaled in the housing 26 and in a lug 35 provided in the housing 26. A spring 38 yieldingly urges the plunger

34 and the plate 33 to the left (Figs. 1 to 4, inclusive). A pin 39 projecting through the right hand end (Fig. 1) of the plunger 34 is engageable with the lug 35 to limit displacement of the plunger

34 to the left (Fig. 1). The construction is such that when the door is opened, the plate 33 is displaced into the slot 31 by the spring 38 (Figs. 1 and 2).

It will be noted that when the door 10 is in its closed position as illustrated in Figs. 3 and 4, the arm 22 engages the plate 33 and holds the plunger 34 in its retracted position against the action of the spring 38. The plate 33 remains in engagement with the arm 22 during the initial

opening of the door 10 until the plate 33 is dis-

posed in the slot 31 (Fig. 2).

It will be noted that in Fig. 1, the arm 22 engages the lower portion 33a of the plate 33, the plate 33 being cut away to provide a shoulder 33b

above which is a front surface 33c on the plate 33.

The purpose of this construction will presently

appear.

The plunger or wedge member 25 is yieldingly urged in a downward direction by a spring 40 which has its lower end disposed in the recess

45 formed in the upper end of the plunger or wedge member 25. The upper end of the spring 40 is disposed around a pin 40a screw-threaded in a wall of the housing 26. The wedge member 25 is

slidably journaled in lugs 41 and 42 provided in

the housing 26.

A notch 44 is formed in the wedge member 25. A pin 150 projecting into the notch 44 pivots one

end of a link 151 to the wedge member 25. The

notch limits angular displacement of the link 151

55 around the pin 150. A pin 152 projecting from

the other end of the link 151 rides in a slot 154

formed in the free end of a lever 155, the other

end of the lever 155 being pivoted to a wall of the

housing 26 by a pin 156. A slot 158 formed in

the lever 55 intermediate its ends receives a pin 59 projecting from a lever 45 which is pivoted by a pin 46 in the housing 26. The lever 45 is provided with an integral sweep section 50 which is divided into two parts by a lug 51. One sweep section surface is designated by the reference character 52 and the other by the reference character 53. When the lock is assembled as illustrated in Figs. 1 to 6, inclusive, each of the sweep surfaces 52 and 53 will co-operate with a lever 55 mounted on one end of a plug 56 journalled in a barrel 57 of a tumbler lock which is designated generally by the reference character 60. The tumbler lock 60 is actuated by a suitable key and its construction is such that when the door is in its closed position, the lever 55 occupies the position wherein it is shown in Fig. 3. However, if certain latch mechanism hereinafter identified has been adjusted so that the door can be opened from the outer side only by actuating the tumbler lock 60, its key is inserted in the tumbler lock and rotated to rotate the lever 55 in either direction so that the free end of the lever 55 will ride upon the sweep surface 52 or 53 and displace the lever 45 in a clockwise direction (Figs. 1 and 3) to lift the wedge member 25 against the action of the spring 40. The key is rotated until the lever 55 abuts against the lug 51, whereupon the wedge member 25 will occupy the position wherein it is shown in Fig. 1.

A link 62 has one end pivoted to the sweep section 50 by a pin 63, the other end of the link being provided with a slot 64 in which a pin 65 rides. The pin 65 projects from the free end of the L-shaped lever 66 which is pivoted on a pin 67 projecting into the housing 26. The levers 62 and 66 are shown and described in my co-pending application, Serial No. 745,261 and have the same functions in both disclosures. The levers 62 and 66 operatively connect the sweep section 50 with night latch mechanism which is fully described and shown in my co-pending application, Serial No. 745,261.

A pin 69 projecting from the lever 66 intermediate its ends is engageable by cam surfaces formed on a lug 75 which is formed integral with the sleeve 76 and the pin 69 is also engageable with cam surfaces formed upon a lug 77 which is formed integral with the sleeve 78. Normally, the lugs 75 and 77 are alined with each other as illustrated in Fig. 1. The lever 66 then occupies the position wherein it is shown in Fig. 1. However, if the sleeve 78 is angularly displaced in a clockwise direction (Fig. 1) the pin 69 will be displaced to the right (Fig. 1) so that the lever 66 will be angularly displaced in a counter-clockwise direction (Fig. 1). It is also obvious that the sleeve 78 may be displaced in a counter-clockwise direction (Fig. 1) to displace the pin 69 and the lever 66. Likewise, the sleeve 76 may be rotated in either direction to displace the pin 69 and the lever 66.

Formed integral with the sleeve 76 are lugs 80 which provide a slot 81, the purpose of which will presently appear.

It will be readily understood that if the spindle element 82 is turned in either direction the movement will cause one of the cam surfaces on the lug 75 to displace the pin 69 and the lever 66 from the positions wherein they are shown in

Fig. 1. It will also be understood that if the knob (not shown) secured to the spindle element 87 is rotated in either direction, the spindle 87 will cause one of the cam surfaces on the lug 77 to displace the pin 69 and the lever 66 from the position wherein they are shown in Fig. 1. It

will be further understood that such rotation of the spindle element 87 does not rotate the spindle element 86.

If either of the spindle elements 86 or 87 is rotated so that the lever 66 is displaced from the position wherein it is shown in Fig. 1, the link 62 displaces the lever 45 from the position wherein it is shown in Fig. 3 to the position wherein it is shown in Fig. 1, although in the case of Fig. 3, the lever 45 has been displaced through operation of the tumbler lock 60 instead of by rotation of either of the spindle elements 86 and 87.

The lock is provided with improved latch mechanism 100 which is sometimes referred to as a "night latch". The latching mechanism 100 preferably comprises two plungers 101 and 102 which have their outer ends slidably journalled in the striker plate 30 (Fig. 1). The inner end of the plunger 102 is of reduced diameter as indicated at 103 so that an annular shoulder 104 is provided. The end 103 is slidably journalled in a lug 105 projecting into the housing 26. The shoulder 104 is engageable by a pawl 108 pivoted on a pin 108a projecting into the housing 26. A lever 109 has one of its ends pivoted to the free end of the pawl 108, the other end of the lever 109 being provided with a slot 110 in which a pin 111 rides. The pin 111 projects from a lug 112 formed integral with the link 62.

It will be noted that the inner end of the plunger 101 is bent to provide a tongue 118 which is adapted to enter the slot 81. The tongue 118 is slidably journalled in lugs 119 projecting inwardly from a wall of the housing 26.

Secured to the plunger 101 is a detent 122 formed from spring metal. The detent 122 engages a pin 123 projecting from a wall of the housing 26, the construction being such that the detent 122 co-operates with the pin 123 and yieldingly holds the plunger 101 in either its retracted position or its extended position.

Disposed intermediate the plungers 101 and 102 and pivoted on a pin 125 projecting into the housing 26 is a lever 127. One end of the lever 127 engages a notch 128 formed in the plunger 101. The other end of the lever 127 engages a notch 130 formed in the plunger 102. The arrangement is such that if either of the plungers 101 or 102 is pushed manually into its retracted position, the other plunger moves into its extended position. Thus, when the plunger 102 is pushed from the extended position wherein it is shown in Fig. 3, to the retracted position wherein it is shown in Fig. 1, the lever 127 pushes the plunger 101 from the retracted position wherein it is shown in Fig. 3 to its extended position wherein it is shown in Fig. 1.

A spring 109a extends between the lever 127 and the pin 65.

The night latch mechanism comprises sleeves 76 and 78 having alined polygonal holes through which a spindle 85 of well known construction extends, the spindle 85 comprising independently rotatable spindle elements 86 and 87. Door knobs (not shown) are secured in any suitable manner to the outer ends of the spindle elements 86 and 87.

As fully explained in my co-pending application, Serial No. 745,261, angular displacement of the spindle elements 86 in either direction will permit one to open the door 10 unless the door has been locked by adjustment of the tumbler lock 60 or unless the door has been locked by the night latch mechanism. Rotation of the spindle element 87 in either direction will permit

one to open the door 10 from its inner side at any time.

If either of the spindle elements 86 or 87 is rotated so that the lever 66 is displaced from the position wherein it is shown in Fig. 3 to the position wherein it is shown in Fig. 1, the link 62 displaces the lever 45 from the position wherein it is shown in Fig. 3, to the position wherein it is shown in Fig. 1, although in the case of Fig. 1, the lever 10 45 has been displaced through operation of the tumbler lock 60 instead of by rotation of either of the spindle elements 86 and 87.

In Figs. 3 and 4 the door 10 is shown in its closed position. It will be noted that the arm 22 15 extends through the slot 31 and holds the plunger 34 in a retracted position. It will also be noted that a tapered surface 25a at the lower end of the wedge member 25 engages the arm 22 and cooperates with the wall 26a of the housing 26 to 20 clamp the arm 22 firmly between the wedge member 25 and the wall 26a. It will be noted that the wall 26a is disposed adjacent the jamb side of the door, the jamb being shown at 11a. This construction differs from that shown in my co-pending application as in my co-pending application the arm 22 co-operates with the wall of the housing 26 disposed opposite the wall 26a. The present construction is an improvement over that shown in my co-pending application as in the 25 present construction an unauthorized person can not insert an instrument between the free edge of the door 10 and the housing 17 and then work it between the arm 22 and the adjacent wall of the housing 26 and then gradually work the arm 22 out of the housing 26 to disengage it from the wedge member 25 since it will be noted that in my present construction, the wedge member 25 passes through the aperture 22a in the arm 22. This construction is therefore advantageous as it 30 assists in preventing unauthorized manipulation of the lock.

The link 151 has an upwardly extending lug 160 provided with teeth 161 engageable with a tooth 162 which projects from a bar 163, the bar 45 163 being fixed to the housing 26 by screws 164. A spring 165 tends to rotate the link 151 in a clockwise direction (Fig. 1) around the pin 150. It will be readily understood that if an attempt is made to lift the wedge member 25 by pushing 50 against the lower end thereof, the link 151 will tend to pivot around the pin 152 so that one of the teeth 161 will engage the tooth 162. This function of the teeth 161 and 162 is best illustrated in Fig. 3. From an examination of that 55 figure, it will also be understood that if the link 151 is lifted by the lever 155, the link 151 will pivot around the pin 150 a sufficient distance to insure disengagement of the teeth 161 from the tooth 162.

60 In Figs. 3 and 4 the lock is shown in its locked condition. In Figs. 1 and 2 the lock is shown unlocked with the door 10 moved slightly out of its closed position. When the lock 10 is to be unlocked, the lever 45 may be displaced as described above so that the pin 159 will displace the lever 155 angularly to the position wherein it is shown in Fig. 1 so that it will lift the link 151 with its lug 160. The link 151 will lift the wedge member 25 from out of the aperture 22a so that 65 the door may be opened. When the link 151 is lifted by the angular movement of the lever 155, the teeth 161 are moved out of the path of the tooth 162, this movement being against the action of the spring 165.

75 When the lock 10 is in its locked condition as

illustrated in Fig. 3, any attempt by an unauthorized person to insert an instrument into the lock to lift the wedge member 25 will be defeated by the teeth 161 and the tooth 162.

An advantage of the construction embodied in the link 151 and the lever 155 is that a relatively large movement is obtained for the wedge member 25. This is important as when the door sags or shrinks there will be sufficient movement of the wedge member 25 to insure that it will drop 10 into the aperture 22a when one locks the door. The tapered surface 25f on the wedge member 25 is provided to make allowance for shrinkage of the door. The tapered surface 25f simply provides clearance but the tapered surface 25a engages one side of the slot 22a and will be urged downwardly by the spring 40 until it actually contacts that side of the slot.

It will be readily understood that if the free edge of the door sags downwardly a sufficient distance, the arm 22 will ride above the shoulder 33d and engage the surface 33c of the plate 33. This construction is advantageous in the event the mechanism does not function properly and the wedge member 25 enters the aperture 22a only 25 a short distance for, in that event, if the shoulder 33d were not provided one might lift the free edge of the door upward suddenly and bring the wedge member 25 clear of the arm 22 so that the door might be opened by an unauthorized 30 person.

It is understood that when the door is open as illustrated in Fig. 1, the wedge 25 rests upon the plunger 34. Then when the door is moved into its closed position, the arm 22 enters the aperture 31 and displaces the plate 33 and the plunger 34 against the action of the spring 38 until the several parts are in the positions wherein they are shown in Fig. 4, whereupon the wedge 25 is urged downwardly by the spring 40. The door 40 is then secured rigidly in its closed position as the wedge member insures that the arm 22a will contact firmly with the inner surface of the wall 26a. When the door is opened, the arm 22 permits the plate 33 and the plunger 34 to move outwardly so that the wedge member 25 will again be supported by the plunger.

The present lock functions, to a great extent, like the lock described in my said co-pending application. Thus, when the door 10 is 50 moved into its closed position, the door will engage the arm 23 and displace the keeper member 15 from the position wherein it is shown in Fig. 2 to the position wherein it is shown in Fig. 4. During the final closing movement of the 55 door the spring 19 will urge the keeper member in a counter-clockwise direction and therefore will not retard the closing of the door. When the door is in its open position, the keeper member 15 is held yieldingly in the position wherein 60 it is shown in Figure 2 so that the arm 23 projects from the housing 17 and is engageable by the door when the door is closed subsequently.

While I have shown and described certain embodiments of my invention, it is to be understood 65 therefore, that it is capable of many modifications. Changes, therefore, in the construction and arrangement may be made without departing from the spirit and scope of the invention as disclosed in the appended claims, in which it is 70 my intention to claim all novelty inherent in my invention as broadly as permissible, in view of the prior art.

I claim:

1. A lock for a door mounted in a door frame, 75

- which lock comprises a keeper member movably mounted on the door frame, a wedge member carried by the door and movable vertically to engage said keeper member to secure the door in its closed position, means for disengaging said wedge member from said keeper member, and means including toothed means carried by said wedge member to dog said wedge member in operative position to prevent unauthorized manipulation of said wedge member.
2. A lock for a door mounted in a door frame, which lock comprises a keeper member movably mounted on the door frame, a wedge member carried by the door and movable into a position wherein it engages said keeper member to lock the door in its closed position, means carried by the door and adapted to hold the wedge member in a retracted position, said means being adapted to be displaced by said keeper member so that said wedge member may move out of its retracted position and engage the keeper member to lock the door, means for disengaging said wedge member from said keeper member, and toothed means to dog said wedge member in operative position for preventing unauthorized manipulation of said wedge member.
3. A lock for a door mounted in a door frame, which lock comprises a keeper member pivotally mounted on a door to oscillate in a substantially horizontal plane, a wedge member carried by the door and movable vertically into a position wherein it engages said keeper member to lock the door in its closed position, a spring pressed member carried by the door and adapted to hold the wedge member in a retracted position, said spring pressed member being movable into a retracted position by said keeper member and being provided with a shoulder to engage the under side of said keeper member when the door sags a predetermined amount, and means for disengaging said wedge member from said keeper member.
4. A lock for a door mounted in a door frame, which lock comprises a keeper member pivotally mounted on the door frame to oscillate in a substantially horizontal plane, a wedge member carried by the door and movable vertically into a position wherein it engages said keeper member to lock the door in its closed position, a spring pressed plunger controlled by said keeper member and mounted in said door to hold said wedge member in a retracted position, said keeper member being adapted to displace said plunger into a retracted position whereupon said wedge member engages said keeper member, said plunger being provided with a shoulder engageable with the under side of said keeper member when said door sags a predetermined distance, and means for disengaging said wedge member from said keeper member.
5. A lock for a door mounted in a door frame, which lock comprises a two-armed keeper member pivotally mounted in the door frame, one of said arms being engageable by said door to swing said keeper member into its functionally operative position, a plunger carried by said door and engageable by the other of said arms, said other arm being provided with an aperture, a wedge member movably mounted in said door and adapted to pass into said aperture to co-operate with said keeper member to secure the door in its closed position said plunger being adapted to hold said wedge member in a retracted position, and means for disengaging said wedge member from said keeper member.
6. A lock for a door mounted in a door frame having a jamb against which the door shuts, which lock comprises a keeper member movably mounted on the door frame and movable into a position wherein it projects into said door when said door is closed, a housing in the door, a wedge member in the housing and movable vertically to engage said keeper member and clamp the keeper member between the wedge member and the wall of the housing nearest the jamb side of said door, and means for disengaging said wedge member from said keeper member.
7. A lock for a door mounted in a door frame having a jamb against which the door shuts, which lock comprises a keeper member movably mounted on the door frame and movable into a position wherein it projects into said door when said door is closed, a housing in the door, a locking member carried by the housing and movable to engage said keeper member and clamp the keeper member between the locking member and the wall of the housing nearest the jamb side of the door, and means for disengaging said locking member from said keeper member.
8. A lock for a door mounted in a door frame, which lock comprises a keeper member movably mounted on the door frame, a wedge member carried by the door and engageable with said keeper member to secure the door in its closed position, means for disengaging said wedge member from said keeper member, and means including toothed means carried by said wedge member to dog the wedge member in operative position to prevent unauthorized manipulation thereof.
9. A lock for a door mounted in a door frame, which lock comprises a keeper member movably mounted on the door frame, a wedge member carried by the door and engageable with said keeper member to secure the door in its closed position, means including a link pivoted to said wedge member for disengaging it from said keeper member, and means including toothed means carried by said link to dog the wedge member in operative position to prevent unauthorized manipulation thereof.
10. A lock for a door mounted in a door frame, which lock comprises a keeper member movably mounted on the door frame, a wedge member carried by the door and engageable with said keeper member to secure the door in its closed position, means for disengaging said wedge member from said keeper member, and means including toothed means pivoted on said wedge member to dog the wedge member in operative position to prevent unauthorized manipulation thereof.
11. A lock for a door mounted in a door frame, which lock comprises a keeper member movably mounted on the door frame, a lock housing in said door, a wedge member mounted in said housing and engageable with said keeper member to secure the door in its closed position, a member pivoted to said wedge member and provided with a plurality of teeth, a toothed bar secured in said housing, said toothed bar being engageable with the first mentioned teeth to dog the wedge member in operative position to prevent unauthorized manipulation thereof, and means for displacing said pivoted member to disengage said wedge member from said keeper member.

OSCAR F. RITTERBUSCH.
